(57) **CLAIM**

The ornamental design for a vehicle bonnet vent and bezel, as shown and described.

DESCRIPTION

FIG. 1 is a front left perspective view of a vehicle bonnet vent and bezel according to the present invention.

FIG. 2 is a rear left perspective view of the vehicle bonnet vent and bezel shown in FIG. 1.

FIG. 3 is a front right bottom perspective view thereof.

FIG. 4 is a rear right bottom perspective view thereof.

FIG. 5 is a front view thereof.

FIG. 6 is a rear view thereof.

FIG. 7 is a side left view thereof.

FIG. 8 is a side right view thereof.

FIG. 9 is a top view thereof.

FIG. 10 is a bottom view thereof; and,

FIG. 11 is a top view of the vehicle bonnet vent and bezel shown in FIGS. 1-10, but mounted on a vehicle, with the rest of the vehicle shown in de-emphasized and half-tone portions so as to illustrate environmental structure.

More particularly, in FIG. 11, the inventive vehicle bonnet vent and bezel is shown within the broken line, and the elements shown outside the broken line form no part of the claimed invention, but are instead included to show environmental aspects thereof.
